(57) **CLAIM**

The ornamental design for a container for medical implant, as shown and described in FIGS. 1-22.

DESCRIPTION

FIG. 1 is a perspective view of an embodiment of a container for medical implant;

FIG. 2 is another perspective view of the embodiment of the container for medical implant of FIG. 1;

FIG. 3 is a left side view of the embodiment of the container for medical implant of FIG. 1;

FIG. 4 is a right side view of the embodiment of the container for medical implant of FIG. 1;

FIG. 5 is a front view of the embodiment of the container for medical implant of FIG. 1;

FIG. 6 is a rear view of the embodiment of the container for medical implant of FIG. 1;

FIG. 7 is a top view of the embodiment of the container for medical implant of FIG. 1;

FIG. 8 is a bottom view of the embodiment of the container for medical implant of FIG. 1;

FIG. 9 is a perspective view of a body part of the embodiment of the container for medical implant of FIG. 1;

FIG. 10 is a left side view of the body part of the embodiment of the container for medical implant of FIG. 1;

FIG. 11 is a right side view of the body part of the embodiment of the container for medical implant of FIG. 1;

FIG. 12 is a front view of the body part of the embodiment of the container for medical implant of FIG. 1;

FIG. 13 is a rear view of the body part of the embodiment of the container for medical implant of FIG. 1;

FIG. 14 is a top view of the body part of the embodiment of the container for medical implant of FIG. 1;

FIG. 15 is a bottom view of the body part of the embodiment of the container for medical implant of FIG. 1;

FIG. 16 is a perspective view of a cap part of the embodiment of the container for medical implant of FIG. 1;

FIG. 17 is a left side view of the cap part of the embodiment of the container for medical implant of FIG. 1;

FIG. 18 is a right side view of the cap part of the embodiment of the container for medical implant of FIG. 1;

FIG. 19 is a front view of the cap part of the embodiment of the container for medical implant of FIG. 1;

FIG. 20 is a rear view of the cap part of the embodiment of the container for medical implant of FIG. 1;

FIG. 21 is a top view of the cap part of the embodiment of the container for medical implant of FIG. 1; and,

FIG. 22 is a bottom view of the cap part of the embodiment of the container for medical implant of FIG. 1.
